ELECTRIC SWITCH

Joseph Figueira, New York, N. Y., assignor to
 Leviton Manufacturing Company, Brooklyn,
 N. Y., a corporation of New York

Application October 8, 1934, Serial No. 747,297

4 Claims. (Cl. 200—64)

This invention relates to an electric switch of the rotary type that is particularly adapted as a canopy switch, although it is not restricted to this use.

Heretofore canopy switches of the rotary type have been produced in which the switch operating shaft extended through holding means for the switch, which in turn extended through the canopy, and a knurled button was attached to the end of the switch operating member or shaft so that this shaft could be turned by twisting the button with the fingers. For a long time there has been a desire for switches of this sort that could be operated by a pull chain or the like and which at the same time would not occupy an inordinate amount of space or present a cumbersome appearance.

By the present invention a switch of the type referred to is produced in a very economical and efficient manner which can be made so as not to occupy much space and is very free from getting out of order or becoming broken or rapidly worn out.

The invention will be understood from the description in connection with the accompanying drawings in which Fig. 1 is a plan view from the rear of an illustrative embodiment of the invention; Fig. 2 is a section along the line 2—2 of Fig. 1; Fig. 3 is a horizontal section through the switch support and other portions of the device along a plane parallel to the paper; Fig. 4 is a section along the line 4—4 of Fig. 2; Fig. 5 is a plan view of the base of the switch showing some of the parts; and Figs. 6 and 7 are plan views of some of the details.

In the drawings reference character 1 indicates a somewhat oval shaped base or housing of insulating material having flat sides and also having a recess 2 (Figs. 2 and 5) intermediate the sides for accommodating a make and break member 3 and spring contacts 4 and 5. The spring contacts 4 and 5 are anchored in recesses provided at opposite sides of the recess 2 and these contacts 4 and 5 are electrically connected to the wires 6 and 7, as indicated in Fig. 5.

A metal plate 8 (Fig. 2) lies along the lower side of the portion of the make and break member 3 that is made of porcelain or similar rigid insulating material and this plate 8 is provided with arms 9 extending at right angles to the plate and lying along the outer sloping surfaces of alternate teeth on the insulating member 3 so that this member 3 can be turned in a clockwise direction, as shown in Fig. 5, to close the circuit between the contacts 4 and 5, but will be

prevented from turning in the opposite direction by the radially extending portions of the teeth contacting with the ends of the contacts 4 and 5. A polygonal, preferably square hole 10, is provided in the member 3 to receive a correspondingly shaped shaft 11 for turning the member 3. The outer end of the polygonal or square shaft 11 is reduced and rounded, as indicated at 12.

A sheet of insulating material 13 (Fig. 2) of the same shape as the base 1 closes the recess 2 and has a central opening through which the shaft 11 extends. A metal plate 14 lies upon the insulating plate 13 and is provided with lugs 15 bent at right angles to the plate 14 and extending across the edges of the plate 13 to keep it in place. The plate 14 is also provided with arms 15 that extend along the flat sides of the base 1 (Fig. 1). These arms 15 are reduced at their outer ends and bent over behind the base 1, as shown at 16, thus securing the plate 14 to the base 1.

A metal disc 17 (Figs. 2, 4 and 7) that is provided with teeth 18 has a square hole 17' in which the shaft 11 fits. The disc 17 lies upon the plate 14 and is free to turn with the shaft 11, as will be described below.

An operating member 19 for the disc 17 is provided with a flanged opening 19' sufficiently large to permit the shaft 11 to extend therethrough and turn freely therein. A pull chain 20 or the like is connected to the curved flange 21 on the member 19 by slipping a link of this chain into the notch 21' in the well known way. A tongue 22 (Figs. 3, 4 and 6) is struck downwardly from the member 19 in such a position that the end thereof strikes the edges of the teeth 18 of the disc 17 in succession as the chain 20 is pulled, thus turning the disc 17, shaft 11 and make and break device 3, thereby alternately opening and closing the circuit.

A coil spring 23 is provided for returning the member 19 after the chain 20 has been released. One end of the spring 23 engages a notch 24 in the flange 21 and the other end of this spring engages one side of a tongue that will now be described.

A tongue 25 is struck up from the plate 14 at right angles and is again bent at right angles to provide a portion 26 that is parallel to the plate 14 and against the edge of which portion one end of the spring 23 rests. The portion 26 is provided with a hole 26' which serves as a bearing for the reduced portion 12 of the shaft 11. The shoulder on the shaft 11 near this reduced portion prevents the shaft 11 from becoming displaced.

A cup shaped metal casing 27 encloses the switch operating mechanism that has been described. Portions 28 of the walls of the cup shaped casing 27 extend short distances along the flat sides of the base 1 (Fig. 1). Notches 29 (Fig. 2) are provided along opposite edges of the casing 27 so that this portion of the casing rests upon the sheet of insulating material 13. This portion of the casing 27 is also provided with notches 30 to accommodate the lugs 15.

The edges 31 of the rim of the member 27 are crimped inwardly at the ends of the portions 28 over the portions 32 of the metal plate 14 near the edges of the arms 15, which extend beyond the straight sides of the base 1, as shown in Figs. 1 and 3, to keep the member 27 securely attached to the remainder of the device. A hole 33 is shown in the casing 27 into which the end 12 of the shaft 11 projects.

An opening 34 is provided in one side of the casing 27. An externally threaded nipple 35 is provided with a reduced end 36 that extends through the opening 34 and is flanged outwardly with a washer 37 between this flange and the inside wall of the casing 27, thus keeping the nipple 35 securely in place. A knurled nut 38 is screwed on the nipple 35 and the chain 20 extends through the nipple 35 and nut 38.

The switch may be retained in place by having a hole in a canopy through which the nipple 35 projects and screwing the nut 38 against the outer face of the canopy wall, thus clamping this portion of the canopy wall between the nut 38 and the casing 27. Or, a threaded washer 35 may be provided on the nipple 35 between the casing 27 and the inside wall of the canopy, or the switch can be retained in place in any other convenient way.

The operation of the device is similar to similar devices that are provided with a button on the operating shaft of the make and break device, except that the circuit is alternately opened and closed with the present device by successive pulls on the chain 20, or other flexible operating member that is attached to the member 19. However, this device possesses the advantage of eliminating the danger of the turning of the shaft 12 by one pull of the chain 20 being so great as to cause the member 3 to be turned a sufficient distance to open the circuit and immediately thereafter close the same, or vice versa.

The reason for this is that one end of the curved flange 21 strikes against one edge of the tongue 25 when the chain is pulled before the member 3 is turned too far, and the other end of the flange 21 strikes against the other edge of the tongue 25 before the spring 23 turns the member 19 back a sufficient distance to cause the end of the tongue 22 to catch behind the wrong tooth 18 when the chain 20 is released.

I claim:

1. In an electric switch, a base, a revoluble make and break device in said base, an axially extending shaft for operating said make and break device, a metal plate through which said shaft passes attached to said base, a struck up tongue from said plate having a journal for said shaft, and mechanism for operating said shaft, said shaft operating mechanism being located between said plate and tongue.

2. In an electric switch, a base, a revoluble make and break device in said base, an axially extending shaft for operating said make and break device, a metal plate through which said shaft passes attached to said base, mechanism for operating said shaft, and a metal housing for said shaft operating mechanism attached to said metal plate on the other side of said plate from said housing.

3. In an electric switch, a base, a revoluble make and break device in said base, an axially extending shaft for operating said make and break device, a metal plate through which said shaft passes attached to said base, mechanism for operating said shaft, and a metal housing for said shaft operating mechanism attached to said metal plate by having portions of the wall thereof bent under extending portions of said plate.

4. In an electric switch, a base of insulating material having a recess, therein, a revoluble make and break device in said recess, a shaft for operating said make and break device, a sheet of insulation and a metal plate closing said recess and provided with openings for said shaft, a struck-up tongue from said plate having a journal for said shaft, operating means for said shaft located between said tongue and said plate, and a metal housing for said shaft operating means attached to said base and located on the other side of said sheet and plate from said base.

JOSEPH FIGUEIRA.
